CLAIM

The ornamental design for a marker airbrush, as shown and described.

DESCRIPTION

FIG. 1 is a front, right and top perspective view of a marker airbrush, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, right and top perspective view of the marker airbrush in use state;

FIG. 9 is a rear, right and top perspective view of the marker airbrush in use state; and,

FIG. 10 is a rear, right and top perspective view of the marker airbrush in use state.

The broken lines shown in the drawings illustrate portions of the marker airbrush that form no part of the claimed design.
